ARTICLE RACK FOR A DRAFTING TABLE

Emerald R. Blue, Washington, D.C.

Application June 15, 1959, Serial No. 56,361

Term of patent 14 years

(Cl. D33—3)

(Granted under Title 35, U.S. Code (1952), sec. 266)

Figure 1 is a perspective view of an article rack for a drafting table, showing my new design;

Figure 2 is a bottom plan view;

Figure 3 is a sectional view taken on the line 3—3 of Fig. 1, looking in the direction of the arrows; and

Figure 4 is a sectional view taken on the line 4—4 of Fig. 1, looking in the direction of the arrows.

The side not shown is the same in appearance as the side shown and the broken line showing of ink bottles, a roll of tape, and a portion of a drafting table is for illustrative purposes only.

The invention described herein, if patented, may be manufactured and used by or for the Government for governmental purposes, without the payment to me of any royalty thereon.

I claim:

The ornamental design for an article rack for a drafting table, substantially as shown and described.
